UNITED STATES PATENT OFFICE.

HENRY R. CORKHILL, JR., OF ROCHESTER, NEW YORK, ASSIGNOR TO THE STECHER LITHOGRAPHIC COMPANY, OF SAME PLACE.

MULTICOLOR-PRINTING PRESS.

SPECIFICATION forming part of Letters Patent No. 532,417, dated January 8, 1895.

Application filed September 19, 1893. Serial No. 485,811. (No model.)

To all whom it may concern:

Be it known that I, HENRY R. CORKHILL, Jr., of Rochester, in the county of Monroe and State of New York, have invented certain new and useful Improvements in Multicolor-Printing Presses; and I do hereby declare the following to be a full, clear, and exact description of the same, reference being had to the accompanying drawings, forming a part of this specification, and to the reference numerals marked thereon.

My present invention has for its object to provide a machine adapted to print upon a web of paper, pasteboard, or similar material, from several forms, and preferably in different colors, which web may be afterward severed into sections or pieces, preferably adapted for making knock-down boxes or cartons, though capable of being used for other purposes, and to these and other ends, it consists in certain improvements in construction and combinations of parts, all as will be hereinafter fully described and the novel features pointed out particularly in the claims at the end of this specification.

In the accompanying drawings:—Figure 1 is a side elevation of a machine or press constructed in accordance with my invention; Fig. 2, a view of the opposite side; Fig. 3, a detail of the supply-roll and brake; Fig. 4, a longitudinal sectional view of the machine; Fig. 5, a cross-sectional view; Fig. 6, an enlarged side elevation of one of the inking devices; Fig. 7, a section on the line $y-y$ of Fig. 8; Fig. 8, a detail view of one of the inking rollers and its bearing, the devices for adjusting the latter being shown in sections; Fig. 9, a sectional view on the line $z-z$ of Fig. 7; Fig. 9^a, a sectional view on the line $a-b$ of Fig. 1; Fig. 10, a section on the line $c-d$ of Fig. 9; Fig. 11, a cross-sectional view of one of the impression cylinders carrying the printing form; Fig. 12, a longitudinal sectional view of one end of the same; Fig. 13, a perspective view of one of the printing form cylinders showing the adjusting devices for the form; Fig. 14, a sectional view on the line $e-f$ of Fig. 5; Fig. 15, a sectional view on the line $g-h$ of Fig. 1.

Similar reference numerals in the several figures indicate similar parts.

The main frame of the machine is composed

of side pieces 1, 1, connected by suitable tie rods or bolts 2, and resting upon and secured to a base frame or casting 3.

4 indicates a cross-shaft supported in suitable bearings 5 in the main frame carrying the main cylinder or cylindrical platen 6 arranged between the sides of the frame. Upon the outer end of the shaft 4 is arranged a large gear wheel 7, and meshing with this gear-wheel is a gear 8 on a shaft 9, which latter is also provided with a belt pulley 10 and fly-wheel 11 and actuated from a suitable prime mover.

13 indicates a frame mounted upon the base frame 3 at one end of the machine having upon its upper end a shaft 14, upon which the roll 15 of paper or cardboard to be printed is mounted; the web 16 of said paper extending under a suitable guide pulley or roller 17, over a small scraper 18 and another guide pulley 19, thence around the cylinder or platen 6, (around the periphery of which the cylinders carrying the printing forms are disposed,) and through suitable tension and severing devices, as will be presently described.

Upon the end of the shaft 14, carrying the roll of paper, is a suitable pulley or drum 20 having a groove in its periphery receiving one end of an arm 21, through which passes a threaded shaft 22 having a handle 23, and by operating the latter the shaft 14 and roll of paper may be moved back and forth in its bearings in the frame 13 to provide for the endwise adjustment of the roll and properly position the web on the cylinder 6. The lower end of the arm 21 operates in a longitudinal groove in a stud 24 and is thereby steadied, and pivoted upon the stud 24 is a lever 25 suitably weighted and connected to a brake strap 26 passing over pulley 20 and secured to the frame 13, as shown in Figs. 2 and 3, thereby giving the necessary tension to the paper web, while permitting its lateral adjustment, as described.

In the present embodiment of my invention I have shown five printing cylinders or type forms arranged around the main cylinder or platen 6, adapted to print upon the web in five colors, or in any less number, but it will be understood that a greater or less number of forms could be employed if desired, and as these forms and their inking devices

55

100

are all similar, a description of one of them will suffice.

For convenience of description, I will term the cylinders, on which the forms from which it is desirable to print, type cylinders, though, as farther on explained, the forms are preferably etched zinc plates, and each contain the part of the complete matter that is to be printed in a single color.

10 Each of the type cylinders is mounted upon a shaft 27 adjustably supported in bearings 28 in the main frame, which bearings are capable of vertical adjustment by means of adjusting screws, as shown, and upon the outer 15 end of said shaft is a disk 29 to which is connected a gear 30, by means of bolts 31 operating in suitable slots in the gear and permitting a slight rotary movement to provide for the rotary adjustment of the type form 20 independently of the cylinder 6, and of the other type cylinders. The shaft is further provided with a collar 32 in one end, and at the opposite end with a nut 33 for clamping the cylinder securely to it, and set nuts 34 25 are arranged on the shaft next the bearings 28 by means of which the longitudinal adjustments of the cylinders can be accomplished, as will be understood.

The printing or type cylinders are composed 30 of a central core piece 35 encircling the shaft 27 and provided with two or more circumferential undercut grooves 36 and with a longitudinal dovetailed groove 37, and arranged over this core are preferably two semicircular 35 sections 38, held in position by screws 39 engaging blocks 40 fitting the grooves 36, and capable of a slight rotary motion on the core 35. The proximate sides of said sections 38 are arranged at an angle with each other between which operates a sliding wedge or key 41, its outer periphery being flush with the sections 38, while its inner side is, provided with a dovetail projection fitting the groove 37 in the core 35. A gear 42 is arranged between the collar 32 on the shaft and the cylinder, through which operates a suitable screw 43 screwing into the end of the wedge 41. The printing form 44, preferably of etched zinc, or, if desired, a stereotyped form, is secured around the cylinder with its ends fastened to the sections 38 of the cylinder by screws 45, as shown in Fig. 11, and after being thus secured is tightened by operating the screw 43, which will draw the wedge 41 55 longitudinally of the cylinder, separating the sections 38, their attached blocks 40 sliding in the grooves, and causing the surface of the printing plate or form to fit the cylinder tightly, the surface of the wedge 41 being flush with the outer surface of the cylinder making a smooth support for the form, which is necessary to insure good work.

It will be understood that larger or smaller printing forms may be employed by the use 65 of different sized cylinder sections 38, and to permit this, it is, of course, necessary that the inking apparatus of each of the cylinders

be adjustable, and this I accomplish in the manner now described.

Secured to the side pieces 1 of the main frame and preferably forming cap plates for the recesses in which the bearings of the type cylinders operate, are castings or frames 46 provided with ways on their inner sides in which slide castings or frames 47 carrying the inking apparatus and adjustable by means of screws 48 connected by beveled pinions 49 through a shaft 50 for causing the simultaneous vertical adjustment of the two frames, the ends of said shaft 50 being squared for the application of a wrench. In each of the said castings 47 are arranged ways for receiving bearing blocks 51, which are vertically adjustable by means of set screws 52, and each of these blocks is provided with an inwardly projecting boss 53, in which operates the shaft of the ink roller 54, one of said ink rollers being arranged on each side of the center of the type-cylinder to which it belongs. Mounted upon the sleeves 53 are 90 radius arms 55, their upper ends being split and capable of being tightened around the sleeves, by screws 56, as shown in Figs. 7 and 8, while the lower ends of said arms are provided with cylindrical apertures in which are 95 arranged sleeves or bushings 57, having eccentrically arranged apertures in which the ends of the inking rollers 58 are located, said sleeves being secured in any position of rotary adjustment by means of a securing plate 100 59 mounted on the arm 55 and engaging the roughened outer edge, as shown in Fig. 9.

The inking rollers 58 are adapted to apply ink to the surface of the type form or cylinder and by means of the bushings 57, their surfaces may be adjusted relative to the surface of the rollers 54 to compensate for any shrinkage, and the radius arm 55 will insure their proper position relative to the rollers 54, as will be understood, even when type cylinders of different sizes are used.

Arranged between the bearings 51 are loose bearing-blocks 60 (see Figs. 5 and 14) in which an inking roller 61 has its bearings; said roller being provided with a gear 62 at one end meshing with the gear 42 on the type-cylinder and also with gears 63 arranged on one end of each of the rollers 54, as shown particularly in Fig. 1. The upper portions of the bearing blocks 60 are slotted for the accommodation of the ends of a roller 64 resting upon the surface of the rollers 54 and permitted a free longitudinal movement caused by a traveling distributing roller or vibrator 65 arranged upon a double threaded shaft 66; said roller 65 receiving ink from a vibrating roller or ductor 67 supported upon arms 68 attached to a rock shaft 69, the latter being provided with an arm 70 having a slotted lower end, which latter is oscillated by a slide or cross-head 71 provided with a pin 72 operating in the slotted end of the arm; said cross-head being provided with pins 73 and moved back and forth by a cam 74 arranged on the end of the shaft

27, as shown in Figs. 5 and 6. The ductor-
roller 67 is adapted, by means of the devices
just described, to be brought in contact with
a roller 76, the latter operating in an ink-well
5 77 and moved intermittently, through a rock
arm 78 carrying a pawl 75 and connected by
a pitman 79 with a crank-pin 80 arranged on
the cam 74, or otherwise connected to the shaft
of the type-cylinder. The shaft 66, it will be
10 understood, is prevented from longitudinal
movement, but as motion is communicated to
the roller 64 and by this to the roller 65, the
latter will, as it rotates, carry both said last
mentioned rollers back and forth distributing
15 the ink evenly upon the rollers 54, from which,
by rollers 58 and 61, the ink is deposited upon
the type-cylinders.

From the above it will be seen that the ro-
tary adjustment of the various type-cylinders
20 can be accomplished by the slotted connection
between the gears 30 and the collars 29 on the
type-cylinder-shafts, and that the longitudi-
nal adjustment of the shafts and type-cylin-
ders can be accomplished by means of the set
25 nuts 34, so that the proper register on the
paper or pasteboard web can be readily ac-
complished and the several colors or forms
printed in proper position.

At the rear end of the machine, shown at
30 the right in Figs. 1 and 4, and at the left in
Fig. 2, is provided a device for giving tension
to the paper and preventing its wrinkling on
the impression cylinder, and also causing the
printed portion to be presented properly to
35 the severing devices, consisting, in the present
instance, of a roller 81 over which the paper
passes and a shaft 82 having collars 83 there-
on operating to press the paper or web tightly
upon the roller 81, the shaft 82 being arranged
40 in an eccentric bushing 84 supported in a sup-
plemental frame 85, so that the pressure be-
tween the roller and the collars may be ad-
justed as desired; set screws 86 serving to
bind said bushings after being adjusted.
45 These two shafts are provided with intermesh-
ing gears 87 driven from a gear 88 on a stud
89, the last mentioned gear being driven from
a gear 90 on a shaft 91, upon which is located
a belt-pulley 92 driven by a belt 93 from a
50 similar pulley 94 on the main driving shaft
9; the gears being so proportioned that the
roller 81 and collars 83 (which latter consti-
tute in effect a roller) are driven at a slightly
greater surface speed than that of the main
55 impression cylinder, so that the paper will be
drawn taut all the time and a slight tension
exerted on it. Just beyond these tension roll-
ers and journaled in suitable bearings in a
frame 95 are two rollers 96 and 97, the former
60 being preferably of metal and solid and the
latter having suitable cutting and scoring
projections or ridges adapted to cut and score
the web on proper lines to make folding boxes
or cartons, for instance, and beyond these are
65 two rollers 98 and 99 connected for simulta-
neous rotation by gears 100. The boxes 101
for the rollers 99 are supported upon springs

102 (see Fig. 10) and capable of vertical mo-
tion; said springs serving normally to sepa-
rate the rollers, but arranged over the boxes 70
101 is a shaft 103 having at opposite ends,
cams 105 operating upon the boxes and serv-
ing, when the shaft is rotated in one direc-
tion, to depress the boxes and bring the roll-
ers into contact. The end of the shaft 103 is 75
provided with an arm 104 adapted to be actuated
by a crank pin 106 on a gear 107 at-
tached to the roller 97, as shown in Fig. 1,
gears 108 transmitting motion to the rollers
98 and 99, and operating them at a greater 80
surface speed than the movement of the web,
from which, it will be seen, that when the
rock shaft 103 is moved to bring the rollers 98
and 99 into contact, the previously cut and
scored web will be grasped and drawn out- 85
ward, separating the box blanks, for instance,
from the web and delivering said blanks at
the end of the machine separately, so that
they may be readily stacked and folded and
the small pieces of pasteboard that may be 90
adhering to them readily shaken off.

The scoring and separating devices are
driven from the main gear wheel 7 through
the medium of the double gears 109, 110, the
latter meshing with a pinion 111 and the 95
former connected adjustably to it by means
of bolts 112, as shown in Fig. 1, and meshing
with the main gear 7. Both the gears 109
and 110 are mounted upon an adjustable
stud 113 operating in a slot in an arm 114 100
pivoted at 115 to the main frame and said
arm is adapted to be secured by a bolt 116
operating through its lower slotted end.
This arrangement not only permits the re-
moval of the cutting and scoring apparatus, 105
but also permits its proper adjustment or
alignment with regard to the web, and the
variations of its speed relative to the main
impression cylinder, by the substitution of
other gears for gears 109 and 110, the verti- 110
cal adjustment of the latter being readily ac-
complished.

The operation of the whole machine will
now be apparent. The forms being placed
upon the type-cylinders in the manner de- 115
scribed and by the various adjustments of
the parts, caused to register properly, so as
to print successively in several colors if de-
sired upon the web or material, then as the
web is printed and held under tension by the 120
devices described, it is severed into blanks,
which may consist of plain sheets instead of
folding boxes if desired, and the rapidly re-
volving discharging rollers 98 and 99 serve
to tear the blanks apart and deliver them at 125
the end of the machine.

While I have shown only five type-cyl-
inders, it is obvious that a greater or less
number could be employed, or, if desired to
use only two or more of these shown, the 130
others could be thrown out of operation by
the rotation of the shafts 50, raising the
whole inking devices from the surface of the
impression roller, and then, by means of the

adjusting screws operating on the bearings of the type cylinders not used, lifting them.

This machine though particularly adapted for printing from more or less flexible etched zinc sheets is well adapted for using rigid stereotype plates if desired, attached to what I have termed type-cylinders, by means here described or other equivalent means.

I claim as my invention—

- 5 1. In a printing machine, the combination with the main frame having the radial recess, the main cylinder, and the type cylinder supported in bearings adjustable in said recess, of the removable cap piece extending across the recess in the main frame, the movable slides on the cap pieces, an inking device supported in the slides, and adjusting devices for moving the slides on the cap pieces connected for simultaneous operation, where-
15 20 by the inking device can be bodily adjusted on the cap pieces or removed bodily with them, substantially as described.
2. In a printing machine, the combination with the main cylinder and the gear connected thereto, of the type cylinder, its shaft having two gears, one of them adjustable independently thereof, and engaging the gear on the main cylinder, an inking apparatus adjustable independently of the type cylinder and having a gear engaging the other gear on the shaft, whereby the type cylinder may be adjusted relative to the main cylinder without moving the inking apparatus, substantially as described.
3. The combination with a web-printing machine, of the web-severing rollers, a pair of rollers moving at greater surface speed than the web, the springs for separating them, the rock shaft having the cams, the arm connected to said shaft and the crank-pin on one of the severing rollers for engaging said arm and bringing the rollers together intermittently to grasp the web, substantially as described.
4. In a printing-machine, the combination with the main frame, the main cylinder having the gear, and the plurality of printing cylinders having gears adjustably connected thereto and meshing with the main gear, of the rotary severing devices, the pivoted arm 114, the relatively adjustable gears adjustably mounted on said arm, one of them engaging the gear on the main cylinder and the other actuating the severing devices, substantially as described.
5. In a printing machine, the type or printing cylinder composed of the central core-piece having the longitudinal groove and the segmental outer portions adjustable thereon,

the wedge sliding on the core-piece and en- 60 gaging the segmental parts, and the printing-form fastened to said segmental parts, substantially as described.

6. In a printing machine, the type or print- 65 ing cylinder composed of the central core-piece having the circumferential grooves, the blocks in the grooves and the segmental parts connected to the blocks, the wedge supported upon and movable longitudinally of the core-piece, engaging the segmental parts, and the 70 printing form secured to the segmental parts, substantially as described.

7. In a printing machine, the type or print- 75 ing cylinder composed of the core piece hav- 80 ing the circumferential and longitudinal un- dercut grooves, the blocks in the circumfer- 85 ential grooves, and the segmental parts con- 90 nected to the blocks, the wedge sliding in the longitudinal groove in the core piece and en- 95 gaging the sides of the segmental parts, the screw for moving it, and the type or printing form connected to the segmental parts and 100 extending around the cylinder, substantially as described.

8. The combination with the type cylinder, 85 an ink roller, and the bearings therefor having the bosses, of the radius arms on the bosses, the eccentric sleeves in the radius arms and the inking roller journaled in said sleeves, substantially as described.

9. The combination with the type cylinder and frames 46 arranged over it, of the frames 47 sliding thereon, the ink rollers 54 journaled in said frames, the rollers 58 secured thereto, the rollers 61 and 64 movable independently 95 of the frame, and ink distributing devices, the adjusting screws connecting frames 46 and 47, and connections between them for causing their simultaneous operation, sub- 100 stantially as described.

10. In a printing machine, the type or print- 105 ing cylinder composed of the central core piece, the movable segmental outer parts thereon, a printing form secured to said parts, and means for causing the relative move- 110 ments of the segmental parts to stretch and hold the form, substantially as described.

11. In a printing machine, the type cylin- 110 der composed of the central core piece, the segmental parts movable thereon the adjust- 115 able wedge between them and the printing form connected to the segmental parts and adapted to be clamped and supported by the wedge, substantially as described.
